UNLOADER FOR COMPRESSORS

Edward M. Paullin, Jr., Buffalo, N. Y., assignor to
Worthington Pump and Machinery Corporation,
New York, N. Y., a corporation of Virginia

Application October 9, 1934, Serial No. 747,529

4 Claims. (Cl. 230—31)

This invention relates to unloaders for compressors and an object of the present invention is to provide a simple, practical and positive loading and unloading mechanism for compressors of relatively small capacity, which will be positive in action and will unload the compressor upon the cutting off of operating power thereto and will load the compressor upon the cutting in of operating power.

Another object of the present invention is to provide electrically operated means controlling the loading and unloading of the compressor, which means embodies a mechanism to provide a time lapse between the starting of the compressor and its loading, thereby allowing the compressor and its operating motor to reach full speed before the load torque is imposed.

With these and other objects in view as may appear from the accompanying specification, the invention consists of various features of construction and combination of parts, which will be first described in connection with the accompanying drawings, showing an unloader for compressors of the preferred form, and the features forming the invention will be specifically pointed out in the claims.

In the drawings:

Fig. 1 is a diagrammatic view partly in section showing the improved compressor unloading mechanism.

Fig. 2 is a diagrammatic view partly in section showing a modified form of the compressor unloading mechanism.

Referring more particularly to the drawings, a reciprocating compressor 1, of any approved type, and of relatively small capacity, is shown, which includes the piston 2, suction valve 3 and discharge valve 4. The compressor 1 is driven by an electric motor 5 in the usual manner, that is, through any suitable power transmitting means or coupling.

The compressor 1 discharges through the pipe 6 to the receiver 7, and a check valve 8 is positioned in the pipe 6. The energizing and deenergizing of the motor 5 and consequently the operation of the compressor 1 is controlled by any approved type of control switch 10 which cuts in and out suitable electric current from the line wires 11.

To provide for the unloading of the compressor upon the stopping of its operation and for the loading of the compressor upon the starting, the unloading mechanism 12 is provided. The unloading mechanism 12 comprises a valve 13 which includes a valve cylinder 14 in which is provided a valve seat 15 against which the valve cone 16 rests. A pipe 17 connects to the pipe 6 between a compressor discharge valve 4 and the check valve 8 and it opens into the cylinder 14 on one side of the valve seat 15. A vent open-

ing 18 is formed in the valve cylinder 14 on the opposite side of the valve seat 15 from the connection between the cylinder 14 and the pipe 17. The vent opening 18 may either open to atmosphere or it may be connected to the suction inlet of the compressor.

A valve stem 19 is connected to the valve cone 16 and projects upwardly out of the valve cylinder 14 having its upper end positioned in the path of the valve operating arm 20. The valve operating arm 20 is pivotally mounted as shown at 21 and is connected to the stem 22 of the solenoid operated structure 23. The solenoid operated structure 23 and the arm 20 may be any approved type of construction such as that shown in my companion application, Serial No. 747,528, filed of even date herewith. The solenoid 24 is connected in the line 25 which supplies power to the motor 5 between the motor 5 and the switch 10 so that the solenoid 24 will be energized when the motor 5 is energized. When the motor 5 is deenergized, and consequently when the compressor is stopped, the core 26 of the solenoid 24 will drop and move the arm 20 downwardly, moving the valve cone 16 off the seat 15. The moving of the valve cone 16 off the seat 15 will open the discharge space 4' of the compressor 1 and the pipe 6 between the compressor and the check valve 8 to the vent 18 to permit the bleeding of the pressure fluid out of the pipe 6 and the discharge space 4' for unloading the compressor. When the switch 10 is closed, to start the compressor, the core 26 will move upwardly which will release the arm 20 for upward movement. The arm 20 is moved upwardly by the spring 27; however, its upward movement is retarded by the action of the dashpot structure 28 so that the arm 20 will move slowly and the lapse of a definite period of time will be provided between the energizing of the motor 5 and the closing of the valve 13 by the seating of the cone 16 against the seat 15. During this time interval, the discharge of the compressor 1 will be vented or unloaded through the vent 18. However, when the arm 20 reaches its uppermost position the cone 16 will be seated against the valve seat 15 and the compressor will be loaded. The time interval provided by the retarding of the movement of the arm 20 will permit the motor 5 to attain full speed before the application of the torque load thereon. The unloading mechanism and apparatus illustrated in Fig. 1 and above described, is applicable for compressors of relatively small size and capacity, and for compressors of large size and capacity it becomes practically impossible to pass a sufficient quantity of air or gas through the valve 13, for properly unloading the compressor. To provide for the proper unloading of compressors of larger sizes or capacities than can be effec-

tively unloaded by the structure illustrated in Fig. 1, the modified form of the unloading mechanism as illustrated in Fig. 2, is provided.

In this modified form of construction, it is to be understood that it is applicable for use with compressors of relatively small size in comparison with the larger type industrial compressor. In this form the compressor 40 includes the piston 41 which reciprocates in the cylinder 42 and is operated by the electric motor 43 through the medium of any suitable type of power transmission mechanism. The compressor 40 has an intake valve 44 and a discharge valve 45. The cylinder 42 is provided with a discharge passage or chamber 46 from which the fluid compressed passes into the pipe 47. From the pipe 47 the compressed fluid passes to the receiver 48. If it is so desired a check valve 49 may be placed in the pipe 47.

For unloading the compressor 40, the suction valve 44 has an unloading piston 50 connected thereto which reciprocates in the cylinder 51. When the piston 50 is moved inwardly towards the end of the cylinder 42 it opens or holds open the suction valve 44 to permit the compressor 40 to operate in an unloaded or non-compressing condition.

The operation of the piston 50 is controlled by the control mechanism 52. The control mechanism 52 includes the valve structure 53 which is similar to the valve structure 13, differing therefrom in details of construction. The valve structure 53 comprises the cylinder 54 which has two valve seats 55 and 56 formed therein which are engaged by the valve cones 57 and 58 respectively. The valve cones 57 and 58 are connected by a stem 59 and a second stem 60 is connected to the valve cone 58 and projects out of the cylinder 54 into the path of the operating arm 61. One end of the cylinder 54 is connected, through the pipe 62 with the pipe 47 or to the receiver 48 so that fluid compressed, under receiver-pressure may flow into one end of the cylinder. A pipe 63 is connected to the interior of the cylinder 54 intermediate of its end and to the cylinder 51 so that when the valve cone 57 is off its seat, pressure fluid under receiver-pressure may flow through the pipe 62, cylinder 54, pipe 63 into the cylinder 51 for holding open the suction valve 44. When the valve cone 57 is seated against its valve seat 55 and the cone 58 is off the valve seat 56, the interior of the cylinder 51 is then opened through the pipe 63 into the cylinder 54 and vented either to atmosphere or to the suction of the compressor 40 through the vent 64.

The valve operating arm 61 is similar to the valve operating arm 20 and it is in turn operated by the electromagnet or solenoid structure 65, which is just the same as the structure 23 and operates in the same manner for providing the lapsed time interval between the starting of the motor 43 and the loading of the compressor.

The compressor 40 is of approved type having a water jacket 70 for cooling processes. The cooling water enters the water jacket 70 through the inlet pipe 71. A diaphragm operated valve 72 of any approved construction controls the supply of cooling water to the water jacket 70 of the compressor. The diaphragm operated valve 72 is pressure operated, and is connected by the pipe 73 to the pipe 62 so that when the compressor is unloaded, the supply of cooling water to the water jacket 70 will be cut off.

From the foregoing description taken in connection with the accompanying drawings, it will be apparent that an unloading mechanism for air or gas compressors has been provided, which will effectively unload the compressor upon the cutting off of operating power thereto and will maintain the compressor in an unloaded state for a short time interval after the power is again cut to the motor for operating the compressor, after which the compressor will be effectively loaded until the power is again cut off.

It will be understood that the invention is not to be limited to the specific construction or arrangement of parts shown but that they may be widely modified within the invention defined by the claims.

What is claimed is:

1. In a compressor unloading mechanism, the combination, of a compressor, an electric motor for operating the compressor, a valve for controlling the loading and unloading of the compressor, a pivoted lever connected to said valve for positively operating said valve, electrical means connected in circuit with said motor for moving said lever in one direction, means independently of said electrical means connected to said lever for moving it in the direction reversely to the direction of movement of the lever by said electrical means.

2. In a compressor unloading mechanism, the combination, of a compressor, an electric motor for operating the compressor, a valve for controlling the loading and unloading of the compressor, a pivoted lever connected to said valve for positively operating said valve, electrical means connected in circuit with said motor for moving said lever in one direction, means independently of said electrical means connected to said lever for moving it in the direction reversely to the direction of movement of the lever by said electrical means, and means associated with said lever for retarding its movement by said independent means.

3. In a compressor unloading mechanism, the combination, of a compressor, an electric motor for operating said compressor, pressure operated means for unloading said compressor, a valve for delivering pressure fluid to said compressor unloading means, a pivoted lever connected to said valve for positively operating said valve, electrical means connected in circuit with said motor for moving said lever in one direction, means independently of said electric means connected to said lever for moving it in the direction reversely to the direction of movement of the lever by said electrical means.

4. In a compressor unloading mechanism, the combination, of a compressor, an electric motor for operating said compressor, pressure operated means for unloading said compressor, a valve for delivering pressure fluid to said compressor unloading means, a pivoted lever connected to said valve for positively operating said valve, electrical means connected in circuit with said motor for moving said lever in one direction, means independently of said electric means connected to said lever for moving it in the direction reversely to the direction of movement of the lever by said electrical means, and means associated with said lever for retarding its movement by said independent means.

EDWARD M. PAULLIN, JR.
